SAUL SHAPIRO, OF NEW YORK, N. Y., ASSIGNOR TO ARTCRAFT METAL STAMPING CORPORATION, A CORPORATION OF NEW YORK.

LIGHTING FIXTURE.

Application filed March 3, 1926. Serial No. 91,943.

The present invention relates to lighting fixtures utilizing bent straps in their construction and a strap suitable for use in such lighting fixtures.

It has been common in the art to make up lighting fixtures using castings of brass, aluminum, or iron or bent straps of flat stock, generally of strap iron. Thin castings such as are suitable for straps are difficult to cast and are generally unfinished on one side. In most cases, the cross section of the strap iron is rectangular, and in order to suitably ornament fixtures so made, it has been necessary to apply leaves, flowers, rosettes, and the like to overcome the otherwise bare or naked appearance of the straps. A number of these ornaments were sometimes required for each strap. As these straps are bent in various manners, both sides of the strap are visible, and considerable difficulty may be found in providing suitable ornaments on both sides of the strap. Certain finishes, such as silver and gold which may be applied to brass, cannot be satisfactorily applied to iron. Various other difficulties have arisen in the manufacture of high class fixtures of this type, which are overcome by utilizing the strap made up according to the present invention. This new form of strap also improves the appearance of the fixture.

The present invention contemplates a lighting fixture strap having, what may conveniently be described as a double channel shaped cross section, the side edges of the straps being thickened. This form of strap may be made in various manners. Several forms of straps suitable for the purpose are discussed.

A further object of the invention is to provide a lighting fixture which utilizes bent straps wherein the thickened edges of the strap provide ornaments on both the top and both sides of the strap, and so that the straps present a pleasing appearance no matter what angle they are viewed from.

Other and further objects of the invention will appear as the description proceeds.

The accompanying drawings show, for purposes of illustrating the invention, several of the many possible embodiments in

which the present invention may take form, it being understood that the drawings are illustrative of the invention rather than limiting the same.

In these drawings:

Figure 1 is a prespective view of a lighting fixture part made out of strap bent to a shape to illustrate the character of and various uses of the forms of strap herein contemplated;

Figures 2^a, 2^b 2^c and 2^d are perspective views of illustrative forms of strap;

Figure 3 is a sectional view through the strap, showing the manner in which it accommodates fixture wires; and

Figure 4 is a sectional view through the strap, showing the manner in which it may be mounted to the round fixture body common in the art.

As illustrated in the Figure 1, the strap is in the form of a double channel or H-section. It has a thin web 10 in the middle and has thickened edges or ribs, as shown at 11 and 12, which preferably extend the same distance on each side of the neutral axis of the strap. For illustrative purposes, in Figure 1, the lengthwise ornamentation is shown as simulating rope, which may be made by cuts or depressions 13 rolled into the strap along the ribs. Various other forms of ornamentation may be provided along these ribs. Such forms of ornament as pimples, dimples, corrugations, criss cross marks, etc, are suggested as easily obtainable.

These straps may be made in various manners and may be bent and twisted into any desired shape, so that first one side of the strap is visible, and then the other side, as is indicated in Figure 1. Inasmuch as the strap is ornamented on both sides, it will be obvious that the lighting fixture part made out of bent strap will present an ornamented surface in every direction, and that it will be very rigid on account of the shape of the strap section.

One form of strap is shown in Figure 2^a. It is made from a strip of sheet metal by deforming the edges and bending the material onto itself in suitable dies. To make such a strap, sheet brass of suitable thick-

ness, say $\frac{1}{16}$ "', and width, say $1\frac{1}{4}$ " is worked to shape. The web 10^a of the strap may be $\frac{1}{16}$ " x $\frac{1}{2}$ " and the ribs 11^a and 11^b $1\frac{1}{8}$ " x $\frac{3}{32}$ ", making a strap $\frac{3}{4}$ " wide. These 5 ribs are formed by careful die works so that sharp angles appear at 14 and 15. The manner of the folding of the metal is indicated by the discontinuous cross hatching and the light lines 16 and 17. The dies 10 are so shaped that the metal is forced into intimate contact to expel the air. The metal hardens on account of the work done on it, and the ribs are not pressed out of shape when the ornamentation is applied by rolling 15 the rope simulating impressions 13 (or other form of ornament) into it.

It will be noted in Figs. 2^a and 2^b that the solid, longitudinally ribs extend substantially equal amounts above and below 20 the central web portion. The strap is therefore symmetrical about a median plane parallel to the web, passing through AA, Fig. 2^a or A'A', Fig. 2^b. By reason of this symmetry, the strap is bendable with equal 25 facility in either direction, and presents the same appearance from either side. In Fig. 2^a, the seam or line of contact of the parts is indicated at S. This seam is substantially at the center of the rib.

30 Figure 2^b shows another form of strap produced by soldering four strips 18 arranged in pairs on the opposite edges of a flat strap 19. The two strips at each edge cooperate to form a heavy, substantially solid, 35 longitudinally extending bead, as shown. These strips may be half round or of the other shape and provided with such ornament as dimples shown at 20.

40 Figure 2^c shows the strap made out of a flat strip 21 grooved as shown at 22 so that sheet metal mouldings, such as indicated at 23 and 24, may be applied to it.

Figure 2^d shows a form of strap made by 45 cold rolling the stock or by extruding it. Here the web 10^d and ribs 11^d and 12^d are integral.

50 Bent straps of the above nature may be used wherever one could use the ordinary flat stock. The straps of this invention are used as bracket members for supporting the lights in an electric light chandelier. Such use is necessarily a conspicuous one and so it is essential that the strap be ornamental and of pleasing appearance on both sides, since 55 ordinarily both sides of the strap or bracket member are visible when in use. The bracket member according to this invention has the mechanical property of possessing considerable rigidity, yet it is still bendable into 60 desired shapes; it also has what is important and essential in this art, namely, a distinctly ornamental appearance, and is equally ornamental on both sides. Besides producing a fixture having great advantages so 65 far as beauty and ability to finish are con-

cerned, they have decided advantages in assembling fixtures. Several of these advantages are indicated in the drawing.

Figure 3 shows how fixture wires 25 may be held between the ribs 11 and 12 of the bent strap. By having these wires in the channel provided by the form of strap used, these wires are kept in place, and are rendered less conspicuous. The attention is more directed to the ornamental feature, 75 caused by the ornamental edge of the strap, and one overlooks the wires which are present.

As shown in Figure 1, an ornamental leaf, 80 strap or other device may be easily mounted in the channel provided by the thickened edges of the strap. Such an ornament is indicated at 26. In the drawing, no attempt is made to show the details of its ornamentation. This leaf or other ornament 26 will fit in between the beads or thickened edges 11 and 12, and will be held by them in alignment. These ornaments may be attached by soldering, brazing, screws, or otherwise. By selecting suitable ornamentation on these attached parts, it is obvious 85 that the beauty of the fixture may be greatly enhanced. The web of the strap also provides a flat area, indicated at 27, to which one may attach the devices such as 90 couplings for supporting candles or drop lights, or braces, or other parts.

Strap fixtures of the type to which the 95 present invention is particularly adapted to be used, frequently employ small central bodies made of sheet metal or round spindles to which the straps are fastened. The attachment of the bent strap in such a construction is illustrated in Figure 4. The 100 thickened edges 11 and 12, of the strap lie 105 against the body 29 and present a much closer fit than is possible where the ordinary flat strap is used.

The ornamentation may be rolled into the 110 strap after the strap has been formed to shape and in this way the lighting fixture manufacturer may vary the ornamental 115 appearance of the lighting fixture made out of the previously prepared strap. Fixtures using bent straps made out of material such as has been described, present a much finer 120 appearance than fixtures made out of the flat straps heretofore in common use. They are capable of being finished in any desired 125 fashion, and are not restricted to finishes suitable for iron only. There is an absence 130 of large unornamented or bare surfaces. Furthermore, the parallel lines given to the arm by the present construction, make the fixture appear larger in the direction in which the lines extend. The use of this form of strap makes it possible to provide fixtures of the bent strap type in which pleasing ornamentation is provided, no matter in which direction one looks at the fixture.

It is obvious that the invention may be embodied in many forms and constructions, and I wish it to be understood that the particular forms shown are but a few of the 5 many forms. Various modifications and changes being possible, I do not limit myself in any way with respect thereto.

What is claimed is:

1. An ornamental, readily bendable metallic bracket member for use in electric light chandeliers and the like, comprising a longitudinally extending web portion and relatively thick longitudinally extending substantially solid beads extending along the 15 edges of the web, the beads being integral with the web and extending substantially an equal amount above and below the surfaces of the web, whereby the strap is symmetrical about a median plane parallel to the 20 web and presents substantially the same appearance on each side, and is bendable with

equal facility in either direction, the solidity of the beads preventing their collapse during such bending.

2. An ornamental, readily bendable metallic bracket member for use in electric light chandeliers and the like, comprising a longitudinally extending web portion and relatively thick longitudinally extending substantially solid beads extending along the 25 edges of the web, the beads at each edge of the web having a seam extending from one surface of the web to substantially the center of the beads, the metal being in intimate contact along the seam, whereby the strap 30 is symmetrical about a median plane parallel to the web and presents substantially the same appearance on each side, and is bendable with equal facility in either direction, 35 the solidity of the beads preventing their 40 collapse during such bending.

SAUL SHAPIRO.
